(57) CLAIM

I claim the ornamental design for underwear with pockets, as shown and described.

DESCRIPTION

FIG. 1 is a front perspective view of the underwear with pockets.

FIG. 2 is a front view thereof.

FIG. 3 is a rear view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is an enlarged section view of a large pocket from FIG. 4; and,

FIG. 9 is an enlarged section view of a small pocket from of FIG. 5.

The broken lines shown in the drawings depict portions of the underwear with pockets that form no part of the claimed design.
